HANGER PLATE FOR ELECTRIC FIXTURES OR THE LIKE

Carl X. Meyer, St. Louis County, Mo., assignor to Day-Brite Lighting, Inc., St. Louis, Mo., a corporation of Missouri

Application June 20, 1957, Serial No. 46,667

Term of patent 14 years

(Cl. D48—4)

FIG.1

FIG.5

Fig. 1 is a bottom perspective view of a hanger plate for electric fixtures or the like showing my new design; Figs. 2 and 3 are, respectively, top and bottom plan views thereof;

Fig. 4 is a side elevational view of the hanger plate; and

Fig. 5 is an end elevational view thereof.

1 claim:

The ornamental design for a hanger plate for electric fixtures or the like, substantially as shown.
